UNITED STATES PATENT OFFICE.

ALEXANDER WEINBERG, OF PITTSBURGH, AND CHARLES V. LINDERMANN, OF NORTH BRADDOCK, PENNSYLVANIA.

BASEBALL-GAME APPARATUS.

1,396,798.

Specification of Letters Patent. Patented Nov. 15, 1921.

Application filed February 16, 1920. Serial No. 358,961.

To all whom it may concern:

Be it known that we, ALEXANDER WEINBERG and CHARLES V. LINDERMANN, citizens of the United States, residing at Pittsburgh 5 and North Braddock, respectively, in the county of Allegheny and State of Pennsylvania, have invented certain new and useful Improvements in Baseball-Game Apparatus, of which the following is a specification.

Our invention relates to a new and improved base-ball game apparatus, designed 10 to be played by two or more players, and involving the principles and rules of the well known baseball game.

The game apparatus includes a board 15 marked to designate the diamond, bases, etc., corresponding with the usual baseball field, and in addition thereto, the board is provided with certain pockets, barriers, etc., 20 hereinafter described. It is also provided with manually operated pitching and batting mechanisms.

The prime object of our invention is to provide a new and improved baseball game 25 apparatus including means for delivering a ball from the pitcher's box at varying speeds, and also including a swinging bat device and means coöperating therewith whereby the bat may be manipulated to 30 vary the striking force thereof.

In the accompanying drawings which illustrate an application of our invention,

Figure 1 is a plan view of a game apparatus embodying our invention;

Fig. 2 is a side elevational view;

Fig. 3, a longitudinal sectional view, the section being taken on line 3—3 of Fig. 1;

Fig. 4, an enlarged detail view of a portion of the pitching mechanism; and

Fig. 5, a similar view of a portion of the 40 batting mechanism.

Referring to the drawings, the apparatus as illustrated and as preferred includes a board or body 1, a plurality of cross members 2, and a rim or border 3 projecting slightly above the body 1 and extending along the four sides of the body. The inclosed space 4 is arranged to represent a baseball field and 5 designates the diamond 45 of said field. The first, second and third bases are designated by the numerals 6, 7 and 8, and 10 designates a small hole in each base designed to receive a player figure *a* (see Fig. 3). The home plate and 50 batter's box are shown at 11, and the pitch-

er's box by the numeral 12, a portion of the pitcher's box being formed with a slight depression 13, and adjacent thereto the board is formed with a slot 14.

15 designates a series of ball receiving depressions formed in the board and disposed adjacent to the positions occupied by the infield players. 16 represents small holes adapted to receive the player figures. Barriers 17 are provided in the outfield, and 65 18 designates ball-receiving depressions or holes similar to the depressions or holes 15 of the infield. An opening 19 is formed in the border 3, and in playing the game, a ball batted through said opening counts as a 70 home run.

The means for delivering the ball from the pitcher's box to the batter's box and controlling the delivery thereof, as illustrated and as preferred, comprises a rigid 75 bent member positioned on the under side of the board and including a portion 20 extending from a side edge of the board to the pitcher's box, an upwardly projecting end 21, the latter being designed to project 80 through the slot 14, a portion 22 extending parallel with a side edge of the board, a portion 23 extending upwardly through a slot 24, and a handle portion 25.

Handle portion 25 is adapted to operate 85 in an opening 26 formed in the border 3. Guiding and supporting members 27, 28 and 29 for the rigid bent member are provided on the under side of the body 1. 30 designates a coiled spring having one end secured 90 to the body and its other end connected with the bent member.

The rigid bent member is adapted to be drawn back into operative position or into 95 position for throwing or delivering the ball, against the tension of spring 30. This position is shown in Fig. 1, and in order to maintain the said member in this position and to release the same when desired, we provide a spring actuated pivoted lever or 100 trigger device 31. Lever 31 is pivoted at one end to the border 3, as shown by the numeral 32, and is provided near its free end with a notch 33, the latter being adapted to receive the handle portion when the latter is 105 drawn back. Lever 31 at its free end is formed with an inwardly extending bent portion 34, and interposed between said portion and the upper edge of the border is a 110 spring 35. From this construction, it will

be understood that a slight downward pressure exerted upon the free end of the lever will release the handle portion of the rigid bent slideable member, thus permitting said 5 member to be drawn forward by the spring 30 and the portion 21 to strike the ball.

It is highly desirable in playing the game that the player manipulating the pitching mechanism may cause the ball to be delivered 10 at varying speeds, and in order to accomplish this, we have provided means designed to coöperate with the rigid slideable member. These means, as illustrated, include a pivoted member 36 having a portion 37 adapted to 15 be passed into the path of travel of handle portion 25 and thereby limit the forward movement of said handle and the ball striking portion 21, operable in the slot 14. Member 36, which is pivoted to border 3 at 38 is 20 also provided with a portion 39 extending over the upper edge of border 3, and interposed between said edge and portion 39 is a 25 spring 40. By means of the construction just described, the player operating the pitching mechanism may vary the speed of the ball without being observed by the player manipulating the batting mechanism.

The batting mechanism comprises a bat or striking member 41 mounted to swing on a 30 post 42, a spring 43 having a portion wound around post 42 and its ends respectively secured to the board and to member 41 and arranged and adapted to carry member 41 forward or into the dotted line position 35 shown by Fig. 1. 44 indicates a stop against which the bat strikes in its forward swinging movement. 45 and 46 designate jointed arms, arm 45 being connected at one end with the bat and arm 46 pivoted at 47 and 40 having a portion projecting through an opening 48 of the border, the outer end of arm 46 being provided with a thumb piece 49.

Arranged to coöperate with a projecting portion of arm 46, we provide a pivotally 45 mounted arm or lever 50. Lever 50 is pivotally secured to the border at 51 and is provided with notched portions 52 and 53. The function of notch 52 is to engage the projecting portion of arm 46 and to hold the 50 same against the action of spring 43, thus maintaining the bat back in the full line position shown by Fig. 1.

Means are also provided for limiting the movement or travel of arm 46 in one direction, and consequently the swing of the bat, 55 and as shown, we employ for this purpose the notch 53. Lever 50 is provided with an extension 54 designed to straddle the upper edge of the border, and 55 designates a spring disposed between extension 54 and 60 the upper edge of the border.

In operating the batting mechanism, the player opposing the player manipulating the pitching mechanism presses downwardly upon the spring controlled end of lever 50, 65 thus releasing the arm 46. If a partial swing only of the bat is desired, a very slight pressure is exerted on lever 50, a pressure just sufficient to release the arm from notch 52 and permit the arm to be caught by notch 53. 70 If a full swing of the bat is desired, lever 50 is pressed downwardly quickly and with more pressure.

What we claim is:

1. In apparatus of the character described, 75 the combination with a field having a pitcher's and a batter's box, of a spring actuated swinging bat mechanism, means coöperating with the bat mechanism for providing a full or a partial swing of the bat at will, and 80 mechanism for delivering the ball from the pitcher's box in the direction of the bat at different speeds including a spring actuated bent rod, and means co-acting with the rod for limiting the throw of the rod. 85

2. In apparatus of the character described, the combination with a field, of a pitching mechanism for delivering the ball at different speeds including a slideable bent rod having an end portion projecting upwardly 90 from the pitcher's box, and an end portion disposed at the border of the field and provided with a handle portion, a spring secured to the rod, means within the control of the player for releasing the handle, and 95 means within the control of the player for varying the operative movement of the rod.

In testimony whereof we affix our signatures in presence of two witnesses.

ALEXANDER WEINBERG.
CHARLES V. LINDERMAN.
